Application filed July 29, 1902. Serial No. 117,576. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Linings, of which the following is a full, clear, and exact description, reference being had to the accompanying drawing, forming part hereof, in which the invention is represented in front view.

The leading features of the design consist in the representation in relief of the nude figure of a boy standing at a drafting-desk and

holding extended a paper bearing a design. 15
Above the desk a window is shown, and at the sides of the window the plastering is sealed off, permitting the bricks to show.

I claim—

The ornamental design for a fireplace-lining as herein shown and described. 20

In testimony whereof I have hereunto set my hand in the presence of two subscribing witnesses.

THOMAS M. DUDGEON.
